(57) **CLAIM**

The ornamental design for a washing machine, as shown and described.

DESCRIPTION

The patent or application file contains at least one drawing executed in color. Copies of this patent or patent application publication with color drawing(s) will be provided by the Office upon request and payment of the necessary fee.

1. Washing machine

1.1: Front

1.2: Back

1.3: Left

1.4: Right

1.5: Top

1.6: Bottom

1.7: Perspective

The washing machine has a body which has a rectangular cross-section; the top surface of the body is inclined downward and there are two upward protrusions at the top of the body; both left and right side surfaces of the body have grooves similar to channels and have handles recessed inward; there are four feet on the bottom surface.

The portions of the design shown in the colors blue, pink, and red are for the purpose of illustrating portions of the washing machine and form no part of the claimed design.
